UNITED STATES PATENT OFFICE.

LEON S. GREENBERG, OF NEWARK, NEW JERSEY.

MOLDING FLASK.

Application filed February 2, 1923. Serial No. 616,556.

To all whom it may concern:

Be it known that I, LEON S. GREENBERG, of the city of Newark, county of Essex, and State of New Jersey, have invented certain 5 new and useful Improvements in Molding Flasks, of which the following is a full, clear, and exact description.

My invention relates to improvements in molding flasks which, although capable of 10 general use for molding plastic substances and casting metals, is more especially designed for the use of dentists in the molding of dental plates.

The invention as hereinafter disclosed is a 15 further development or improvement in an invention for like subject matter disclosed in my United States Patent No. 1,331,193, dated February 17, 1920, and is especially characterized and differs therefrom in that 20 provision is made for a cutting edge, and with a perceptible lessening of the amount of material needed in its manufacture, with consequent reduction in cost of production.

One of the important objects is to provide 25 a molding flask with cutting edge contact of the several parts instead of the flat contact surface, which results in the separating of any overflow from the mass of plastic substance used by dentists.

Another object of my improvement is to 30 provide on the top piece a multiple of vents for the escape of any surplus substances when expanding, and of gases when molten metal is being cast.

A further object of my invention is to 35 provide a molding flask capable of greater scope of use and of greater simplicity than my prior invention, in that the projecting portions on bottom and middle pieces are constructed with improved uses and permit the escape of the overflow of plastic substances, and furthermore a funnel is provided for pouring molten metal if desired.

With the above and other uses in view, 40 as well as those mentioned in my U. S. Patent No. 1,331,193, the invention consists in the novel construction, combination, and arrangement of parts hereinafter described, and claimed, and illustrated in the accompanying drawing forming a part of the specification, in which:

Figure 1 is a perspective view of the assembled device showing the several parts in a locked position.

Fig. 2 is plan view of the assembled flask, the top plate being partially broken away.

Fig. 3 is a cross section view of the device on line 3—3 of Figure 2, showing contact of the cutting edges, and one of the means for holding the members of the flask together. 60

Fig. 4 is a detail showing funnel for pouring metals.

The molding flask as illustrated in Fig. 1 is composed of a bottom piece or receptacle 1, a middle piece 2, and a top piece or plate 3. Bottom piece 1, Fig. 1, is provided with recesses or apertures formed within projections or extended portions 5^a, 5^b, and 5^c of the general shape shown. Said projections are constructed integral with bottom piece 1 70 slightly above the middle portion thereof so as to permit the heads of locking pins 9^a, 9^b, and 9^c to turn while the device is resting on a flat surface, more clearly shown in Fig. 1. Bottom piece 1 is curved inwardly at 12, so as to present a cutting edge at point of contact at 13 with middle piece 2, best illustrated in Fig. 3. A plurality of openings along cutting edges may be provided for dental use only, but are not necessary. 80

A middle piece 2, Fig. 1, is detachably fastened or locked to bottom piece 1 and to top plate 3 by means of a multiple of double headed locking pins 11^a, 11^b, and 11^c, when desired, which is more clearly shown in Fig. 85

3. Middle piece 2 is constructed as shown in the various views with both its top and bottom portions curved to form a cutting contact edge, as best seen in the cross section view, Fig. 3, the lower edge 14 being in close contact at 13 with the upper edge of bottom piece 1 around both pieces. The upper edge 15 in a similar manner fits in close contact with the top piece 3. Middle piece 2 is also provided with projections integral therewith 10^a, 10^b, and 10^c, which extend through the recesses or apertures provided in projections on top and bottom pieces 1 and 3 respectively. A hole is provided through each projection 10^a, 10^b, and 10^c, 95

through which locking pins 11^a, 11^b, and 11^c respectively are inserted. The shaft of said locking pins 11^a, 11^b, and 11^c may either be straight as shown in Figs. 2 and 3, or may be in the form of a spiral shaft thereby forming a spring which will permit the top piece 3 to give slightly with the expansion of the material which may be enclosed in the assembled device, when locked. These locking pins are each provided on the upper ends thereof with heads 6^a, 6^b, and 6^c, and on the lower ends with similar heads 9^a, 9^b, and 9^c, 105

110

respectively, Figs. 1, 2 and 3. These heads are firmly riveted, pinned or otherwise attached to the locking pins, making what is called double headed locking pins, all of the same general shape, and made to fit their respective recesses snugly, so that when they are turned with the fingers, the device is securely and firmly locked. The turning of one head reciprocally turns the opposite head, and thus the device may be locked or unlocked from the top or bottom as desired.

Top plate 3, Fig. 1, is of the same general shape as the other two principal pieces. It is provided with projections or prongs 4^a, 4^b, and 4^c, forming recesses to correspond and fit over the top of projecting pieces 10^a, 10^b, and 10^c respectively of middle piece 2, Figs. 1 and 2. Top piece 3 is flat on both top and bottom differing in this respect from the other pieces.

Top piece 3 is also provided with a multiple of vent holes at 5 to permit the escape of surplus or expanding substances, and in case of the molding of metals, the escape of gas. For use in casting metals there is also provided a pouring funnel 4, Fig. 4, attached as illustrated to bottom piece 1, but may be located as desired in any other appropriate place. It will be noted that each projecting portion 6 integral with middle piece 2, Fig. 3, extends away from the main ring in such a manner as to leave openings between bottom 1 and top 3 and middle piece 2, which provide a space for taking care of the overflowing plastic substances cut off when the pieces are assembled and clamped and locked, which surplus substances may then be readily removed.

In use my improved molding flask is assembled by applying bottom piece 1 to middle piece 2, into which the prepared molding substance is placed, after which top plate 3 is placed over middle piece 2, and the three pieces are locked by simply half-turning with the fingers each of the double headed locking pins 11^a, 11^b, and 11^c, using preferably the upper heads 6^a, 6^b, and 6^c thereof. A turn of any pin head causes a corresponding motion or turn of the opposite pin head. To unlock the device, again manually half turn each pin head parallel to the recesses, and top plate 3 may then be removed exposing the casting. Another half turn of each double headed locking pin locks middle piece 2 and bottom piece 1 again, which cannot be accomplished with other known dental flasks, and work may be performed on the casting in that position, or it may be entirely removed by repeating the unlocking process.

Various changes within the enlarged scope of the invention may be made in the particular construction of the device, and also in the size and organization of the pieces thereof without departing from the spirit of my invention, such as the addition of one

or more rings or pieces with similar cutting edges, to make a higher and larger molding flask, which is sometimes desirable.

I am aware that prior to my invention vulcanizing or molding flasks have been made comprising top, bottom and middle pieces of the same general shape, and for the same purpose as mine, but not with the peculiar shape and features thereof, or with the novel means for locking provided in my invention, nor with the specially provided cutting edges or spaces for caring for overflowing substances, therefore, I do not claim the device, and combination of pieces thereof, broadly, but what I do claim as my invention, and desire to secure by Letters Patent, is—

1. In a molding flask of the character described, the combination of a bottom piece with upper portion thereof incurved, a middle piece with both lower and upper portions incurved, a top piece, all constructed so that when assembled the points of contact of the three pieces form cutting means to separate any overflowing substance from the mass contained within said pieces, and a plurality of locking pin means for locking said pieces together, as and for the purpose described.

2. A molding flask, comprising a bottom piece with upper portion incurved to form a cutting edge, provided integral therewith with a multiple of extended portions, each containing a recess, a middle piece with both upper and lower portions incurved to form cutting edges at points of contact with bottom and top pieces respectively, said middle piece being also provided with projecting portions extending above and below through respective recesses provided on bottom and top pieces, and through each such projecting portion is inserted a double headed locking pin, a top piece having provided integral therewith with a multiple of extended portions, each containing a recess, and a multiple of double headed locking pin means for locking said pieces together, as and for the purpose described.

3. A dental flask, comprising three freely separable pieces, a bottom, middle and top, capable of being all locked together to make a mold, and also capable of having the top piece detached and then locking the middle and bottom piece together to permit work on the casting without its removal from said mold, the top and bottom pieces being provided integral therewith with a multiple of extended portions with recess in each forming prongs, the middle piece being provided integral therewith with a plurality of projecting portions with hole through each for passage of locking pin means through same and through said respective recesses on top and bottom pieces, the bottom and middle pieces being constructed so that at points of

contact a cutting edge is provided, and locking pin means for locking said pieces together, substantially as described.

4. In combination, a molding flask, comprising a bottom piece provided with a cutting edge on its upper portion and a plurality of projecting portions integral therewith each containing a recess therein, said projecting portions being located substantially above the middle of said bottom piece and a funnel opening to permit entry of molten metal, a middle piece provided with cutting edge on both its upper and lower contact points and a plurality of projecting portions integral therewith, each containing a hole through which a double headed locking pin passes, each of said projecting portions are constructed to extend

above and below through the recesses provided on top and bottom pieces respectively 20 with space to permit room for overflow of any substance escaping from said molding flask, a top plate provided with a plurality of extended portions, each containing a recess forming prongs over which the heads 25 of the respective double headed locking pins pass when locked which at the same turn locks the opposite head under the similar prongs on bottom piece, and a plurality of double headed locking pins. 30

In testimony whereof I affix my signature in the presence of two witnesses.

LEON S. GREENBERG.
